United States Patent Office.

DAVID MARSHALL, OF PITTSBURG, PENNSYLVANIA.

Letters Patent No. 78,219, dated May 26, 1868.

SOCKET-BOARD FOR REED-INSTRUMENTS.

The Schedule referred to in these Letters Patent and making part of the same.

TO ALL WHOM IT MAY CONCERN:

Be it known that I, DAVID MARSHALL, of the city of Pittsburg, in the county of Allegheny, and State of Pennsylvania, have invented a new and useful Improvement in the Socket-Board of Reed Instruments; and I do hereby declare the following to be a full, clear, and exact description thereof, reference being had to the accompanying drawing, making a part of this specification, in which—

Figure 1 is a sectional view of my improved socket-board.

Figure 2, by a bottom view, illustrates my mode of making the same; and

Figure 3, by a sectional view, illustrates my improvement in a modified form.

Like letters of reference indicate like parts in each.

My improvement relates to the construction of the socket-board, and consists in facing the ordinary socket-board with another slotted or socketed board, the sockets in the latter, or facing-board, being shorter than those in the former, or main board, so that the two being fitted together, the main sockets will be covered at their extremities, and between their ends will be left open for the passage of air.

To enable others skilled in the art to make and use my invention, I will proceed to describe its construction and mode of operation.

In the manufacture of reed-instruments, the wind-chest is covered by the socket-board *b*, in which is cut a series of long, narrow slots or sockets, *a*. These sockets are covered by the reed-board *d*, except that in the under side of the reed-board *d*, and immediately over one or both extremities of each socket *a*, reed-cells *c* are cut, into which are fitted the reeds *e*. The air then being forced by bellows through the reeds *e*, produces the musical vibrations.

In my improvement, I face the main socket-board *b*, on its under side, or on the side next the wind-chest, with another slotted or socketed board, *i*, in which are cut slots or sockets *s*, corresponding in number and arrangement to the sockets *a* in the board *b*. These sockets *s* are shorter than the sockets *a*, so that when the two boards are glued together, as shown in the drawings, the board *i* will cover the ends of the sockets *a* immediately under the reed-cells *c*, and leave a long opening along the sockets *s*, and the middle of the sockets *a*, for the passage of air; but I sometimes close up the middle part of the sockets *s*, by inserting a strip, as at *o*, fig. 2, leaving short slots or sockets *s'* for the passage of air; or such short sockets *s'* may be cut directly in the board *i*. The boards *i* and *b* are glued firmly together, so as to give a tight joint and vibrate in unison. Both sockets may, however be cut in the same board, or a single socket, *u*, fig. 3, with inclined ends, may be used with profitable result, the ends being so inclined that the air passing through the reeds shall strike against the inclined faces *u' u'*.

The advantage of this mode of construction is that the currents of air passing through the reeds *e* impinge against the facing-socket board *i*, or against the inclined faces *u'*, and cause it and the board *b*, or the board *b'*, to vibrate in unison therewith, thus giving to the latter somewhat of the character of a sounding-board. Also, the air, after leaving the reeds *e*, has to take a somewhat circuitous route to reach the wind-chest, in consequence of which the musical tone produced is assimilated to that of the pipe-organ. In this way I make musical reed-instruments of a purer and greatly improved quality and strength of tone.

What I claim as my invention, and desire to secure by Letters Patent, is—

The board *i*, placed immediately below and in contact with the socket-board *b*, and having an opening or openings, *s s'*, under each reed, coinciding with but shorter than the openings or sockets *a* in the socket-board, substantially as and for the purpose described.

In testimony whereof, I, the said DAVID MARSHALL, have hereunto set my hand.

Witnesses:

W. BAKEWELL,
ELL TORRANCE.

DAVID MARSHALL.
